UNITED STATES PATENT OFFICE.

JESSE V. PALMER, OF GREENWICH, NEW YORK.

LADY'S UNDERGARMENT.

No. 878,994.

Specification of Letters Patent.

Patented Feb. 11, 1908.

Application filed December 26, 1906. Serial No. 349,446.

To all whom it may concern:

Be it known that I, JESSE V. PALMER, a citizen of the United States, residing at Greenwich, county of Washington, and State of 5 New York, have invented certain new and useful Improvements in Ladies' Undergarments, of which the following is a specification.

The invention relates to such improvements and consists of the novel construction and combination of parts hereinafter described and subsequently claimed.

Reference may be had to the accompanying drawings, and the reference characters 15 marked thereon, which form a part of this specification. Similar characters refer to similar parts in the several figures therein.

Figure 1 of the drawings is a view in elevation of the upper portion of a ladies drawers 20 showing the lapping edges of each back-flap secured to the middle portion of the other back-flap, the leg portions being broken away. Fig. 2 is a view similar to that shown in Fig. 1, showing the back-flaps secured to 25 each other, in a similar manner, but adjusted to lap each other in a greater degree. Fig. 3 is an edge view of a well-known form of clamping device, made on an enlarged scale.

The object of the invention is to provide a 30 three flap drawers having lapping back-flaps with means for securing the lapping flaps together in such a manner that they will, while in use, maintain their positions relatively to each other, being positively secured together 35 at two different points in the upper edges of the flaps, so that the lapping portion of the flaps will not sag one upon the other.

The invention consists in positively securing the lapping portions of the back-flaps together at two points in their upper edges, one at the edge of each flap and the other at the middle portion of the other flap, which middle portion is approximately at the middle point between the two opposite sides of each 45 flap, as will be hereinafter more fully described and subsequently pointed out in the claims.

Referring to the drawings, 1, represents the front-flap, 2, one of the back-flaps, and, 50 3, the other back-flap. The front flap extends down to the broken line, 4, being secured to flap, 2, at 5, and to flap, 3, at 6.

The back-flaps are secured to each other at, 7, the flap, 2, being foldable at the broken line extending from, 7, to 5, and the flap, 3, 55 foldable along the broken line extending from 7, to 6. The upper edges of all the flaps are preferably provided with a waistband, 8, as shown in the drawings. The back-flap, 2, is adapted to be secured to the front-flap, 1, 60 along their neighboring edges by means of the button, 9, adapted to be inserted in the buttonhole, 10, and the neighboring edges of flap, 3, and flap, 1, by a similar button and buttonhole. The back-flaps are preferably 65 of such dimensions that while in use upon a medium sized person the flaps will lap each other about half their width, as shown in Fig. 1, and they may be positively secured to each other in this position in any known 70 manner, as by the clamping-pins, 12 and 14. The waistband of flap, 2, is shown slightly lower than the waistband of flap, 3, for convenience of illustration; but it is obvious that they may be made to exactly register in 75 height when the clamping-pins are attached.

In Fig. 2 the lapping flaps are made to lap in a greater degree to fit a smaller person. It is obvious that the lapping-flaps may be adjusted to any desired position to accommodate the size of any wearer, and be secured in that position in any known manner, as by stitching, by buttons or studs, and a plurality of buttonholes. It is thus possible with the improved garment herein described 85 to produce a perfect fit of the flaps without any puckering or sagging of the various parts to annoy the wearer or any obstacle to the easy fitting of the outer garments.

The clamping device, which is shown, 90 comprises two parts, 20 and 21, each provided at one end with a jaw, 22, and at the other end with operating handles, 23, which parts are pivoted together, and the clamping-spring 25. It is obvious that any other 95 clamping device or means for positively securing the lapping flaps together at the points named might be employed in practicing the invention.

What I claim as new and desire to secure 100 by Letters Patent is

A garment of the character described having its body portion divided into a plurality of overlapping flaps, and a flap-connecting

means positioned at one end of each of said flaps and adapted to detachably and directly engage the top of the opposing flap at a point immediately opposite said ends for adjustably and detachably connecting the tops of the flaps together, whereby the overlapping portions of the flaps at their tops will lie smooth when the garment is worn.

In testimony whereof, I have hereunto set my hand this 21st day of December, 1906.

JESSE V. PALMER.
